Primary Examiner — Sheryl Lane*Assistant Examiner* — Mark T. Philipp(74) *Attorney, Agent, or Firm* — Thomas J. Nikolai; DeWitt LLP(57) **CLAIM**

The ornamental design for an air pump, as shown and described.

DESCRIPTION

FIG. 1 is a perspective view of an air pump, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is an enlarged view according to Area 7 circumscribed within FIG. 2.

In the drawings, the broken lines represent portions of an air pump and form no part of the claimed design; the two-dot chain lines, that are circumscribing the area noted as 7 in FIGS. 2 and 7 are depicting a boundary of the enlarged portion, and form no part of the claimed design.
